UNITED STATES PATENT OFFICE.

HENRY H. DILLE, OF RICHMOND, INDIANA.

LAWN-EDGE TRIMMER.

SPECIFICATION forming part of Letters Patent No. 427,406, dated May 6, 1890.

Application filed August 1, 1889. Serial No. 319,375. (No model.)

To all whom it may concern:

Be it known that I, HENRY H. DILLE, of Richmond, in the county of Wayne, and in the State of Indiana, have invented certain new and useful Improvements in Lawn-Edge Trimmers; and I do hereby declare that the following is a full, clear, and exact description thereof, reference being had to the accompanying drawings, in which—

10 Figure 1 shows a perspective view of my improved lawn-edge trimmer; Fig. 2, a view of the same in side elevation; Fig. 3, a top plan view of the same; Fig. 4, a similar view of the apparatus with the swinging knife-actuating lever removed; Fig. 5, a perspective view of the under side of such lever; Fig. 6, a section of the apparatus on line ww of Fig. 3; Fig. 7, a detail perspective showing the stud on the knife and the notched end of the actuating-lever separated from each other; Fig. 8, a cross-section of the apparatus on line xx of Fig. 3; Fig. 9, a section of one of the supporting-wheels on line yy of Fig. 3; Fig. 10, a plan view of a modified form of my trimmer, and Fig. 11 a similar view of the main frame of such modified form with the swinging blades and the operating-lever removed.

15 Letters of like name and kind refer to like parts in each of the figures.

20 The object of my invention is to provide an improved lawn-edge trimmer; and to this end my invention consists in the trimmer and in the construction, arrangement, and combination of the parts thereof, as hereinafter specified.

25 In the drawings, A designates the main frame of my machine. It is preferably cast in one piece, with studs or short axles a on opposite sides of it for the reception of the hubs of the supporting-wheels B B. Any desired means for holding the wheels upon the studs or axles can be used instead of the pins b b , passing through holes in the studs, as shown in the drawings. The hub of each wheel I 30 prefer to cast with a countersink around the inner end of its axle-receiving opening, as shown at b' in Fig. 9, as such construction enables me to cast the wheel-hub clean and ready to go upon the frame-stud or axle without the necessity of any machine-work or subsequent shaping of the hub or the axle-opening therein.

35 On the front side of the frame A of the apparatus (shown in Figs. 1 to 8, inclusive) are two forwardly-extending fingers C C, having 55 on their inner sides cutting-edges c c , extending outward in opposite directions away from each other, as indicated best in Figs. 3 and 4. The lines of such edges are preferably slightly curved instead of straight, though they can 60 be straight, if desired, without departure from my invention. The upper face of each finger C is made slightly inclined upward from the outer side of the finger to the cutting-edge, so that such edge is higher than the 65 rest of the top surface.

Upon the frame, in line with the center of the space between the two fingers, is the upwardly-extending stud D, upon which is pivoted the swinging knife E, having its opposite sides sharpened to act in conjunction with the cutting-edge on one or the other of fingers C C as the knife swings in one direction or the other over such fingers. The cutting-edges on the swinging knife, which are at the 70 pivotal portion of the latter wider apart than the inner or rear portions of the edges on the fingers, gradually approach each other toward the outer end of the knife, as shown.

75 The result of the described arrangement of the cutting-edges on the fingers and the swinging knife is that an easy shearing cut is secured as the knife swings in either direction. Such swinging knife can be fastened or held in any desired way upon its pivot.

80 As shown in the drawings, there is a bolt d , extending up through the stud D, provided with a nut d' , engaging a washer d^2 , which projects over and engages a portion of the pivotal part of the knife surrounding the stud. 85 The pivotal opening in the knife is preferably made a trifle larger than the stud D, so as not to fit the same too closely, for a purpose to be described hereinafter. Upon the upper side of the knife at a point forward of its pivot-opening is an upwardly-projecting stud E' , made elliptical, as seen in plan view. (See Figs. 3 and 4.) In the upper end of this stud is a depression or hollow E^2 . Extending rearward from the pivotal portion of the knife E is the arm E^3 , in line with the middle line of the blade. In the drawings I show the knife as also provided with a vertical rib E^4 , extending centrally along its top, and an an-

nular rib or flange E⁵, extending around the portion of the knife engaged by the washer d². Such flanges or ribs can, however, be dispensed with, if desired, without departure from my invention. The sides of stud E' on the swinging knife are slightly inclined upward and inward, so as to approach each other toward the top of the stud.

The frame A has its rear portion elevated, so that its upper surface is above the knife-pivot stud D and the bolt and nut for holding the knife in place on such stud. Arranged on this elevated part of the frame, in line with the center of the space between the cutting-edges on fingers C C and the stud D, is another pivot-stud F, upon which is pivoted the lever G, having its forward end projecting over the swinging knife E, provided with a notch or slot g, engaging the stud E' on said knife. On the underside of the lever are two downwardly-extending lugs g' g', situated so as to stand on opposite sides of the arm E³ and in the path of such arm as the lever and knife E are swung in one direction or the other. As the arm travels in a direction opposite to the cutting portion of the blade and the lever G, each lug g' will when it engages the arm E³ act as a stop to prevent its further movement, and so limit the motion of the knife and lever. The lugs are arranged at such distance apart that they will not meet and engage the arm E³ until the knife E has swung far enough to carry its cutting edges or sides over the edges on arms C C. The lever G is shown as held upon its pivot-stud F in the same way as knife E by means of a bolt g², nut g³, and washer g⁴. Attached to lever G is a strong spring-arm H, whose forward end engages the top of stud E' on the swinging knife, so as to press said knife down and hold it so as it swings from side to side over the edges on the fingers. Extending upward and rearward from the elevated part of the frame is an arm I for attachment of a suitable handle I'. The lever G has a similar arm I² for attachment of the operating-handle I³, of any desired form or length.

The swinging knife is preferably made concave on its under side, as indicated in Fig. 8, to facilitate the formation and maintaining of the desired sharp cutting-edges at its sides during use of the machine.

In the modified form of trimmer, as shown in Figs. 10 and 11, there are three fingers C C and two swinging knives E. The middle finger is a tapering one, with its sides approaching each other toward its point, preferably on a curved line. Both sides of such finger have the cutting-edges c c, and the upper face of the finger is preferably made slightly concave or grooved longitudinally, with the sides of the concavity or groove inclined upward toward the opposite cutting-edges. There are on the frame two pivot-studs D D, upon which are pivoted the two knives E, similar in construction to the knife

shown and described hereinbefore. Each of such studs is situated to the rear of one of the spaces between the center finger and one of the outer fingers and in line with the middle of such space. The knife-actuating lever, pivoted, as before, upon a stud F, has two notches or slots g g, each engaging the stud E' on one of the knives, and two springs H H, each pressing down upon one of such studs, so as to force the respective knife downward toward the plane of the edges in conjunction with which its edges are to act.

The size of wheel which I prefer for supporting the frame A is about three and one-half inches in diameter.

The bottom of the lowest portion of the frame, with fingers C C, I make so as to be about three-quarters of an inch from the lower face of the wheels. These proportions and dimensions, while they are what I prefer, can be varied as desired without departure from my invention.

It will be observed from the drawings that in the single form of machine the two fingers and in the double form the two outer fingers not only have their inner cutting-edges extending forward and outward in diverging lines, but are themselves also inclined away from each other.

The operation of my machine, which will be understood from the drawings and hereinbefore-given description, is briefly as follows: While tilted at any desired angle the machine can be moved along and the knife or knives can be swung by lever G so as to cut any grass or weeds coming between the fingers against the cutting-edges on the latter. With such cutting-edges curved and extending outward from each other, as described, and the edges of the swinging knife extending in lines converging toward the forward end of the knife, an easy shearing or drawing cut can always be secured. The spring H, provided for each swinging knife, bearing, as it does, upon the stud which is beyond and forward of the knife-pivot, forces the knife downward, so that it always shears closely over the edges of the fingers. With the knife-pivot opening fitting the pivot-stud loosely, as described hereinbefore, the knife can yield to this action of the spring. With the sides of the stud E' on the knife inclined, or the stud made slightly tapering upward, as described, the engagement of the sides of the notch or slot g in the actuating-lever with the stud sides will also tend to force the swinging knife into close contact with the finger-edges as it passes over the latter, and the greater the resistance of the article being cut and the greater the power required to cut it the closer will the knife be caused to bind the cutting-edge of the finger. As each swinging blade is thus caused to pass in close contact with the edges of the fingers, its own edges will be kept sharpened. The concaving of the under side of the knife leaves only a small portion of metal along each side of the blade

to be worn or rubbed away, so as to keep the knife-edges sharp. The spring H, as the knife or the fingers are worn away, will always force the knife farther down, so as to 5 always keep its edges in proper cutting relation to the finger-edges.

The operation of the double form of machine is precisely like that of the single one, except that the two knives cut alternately 10 against the inner edges of the outer fingers and the edges of the middle finger.

With my machine constructed as shown 15 and described grass or weeds can be cut along lawn-edges, beside walls or curbs, and even in right-angled corners. Every blade of grass close to a wall can easily be cut if the machine be moved along and operated with one of its fingers passing along the wall-face. The machine can also be successfully operated 20 when turned at any angle to suit the surface over which it is being moved.

If desired, the cutting-edges of the fingers, instead of being formed on the fingers themselves, can be on suitable ledger-plates fastened 25 to the fingers.

I prefer to make the slot or notch g in the 30 end of lever G with its walls inclined at a slight angle downwardly and outwardly away from each other, as indicated in Figs. 5 and 7. The angle of such inclination is the same as that of the sides of the stud E. Such an arrangement I prefer, as it insures the best engagement of the slot sides with the stud and also the best results in forcing the knife 35 down closer to the finger-edges whenever there is any resistance to the cutting action, as described hereinbefore.

Having thus described my invention, what I claim is—

40 1. In a lawn-edge trimmer, in combination with a suitable frame having fingers provided with cutting-edges, the swinging knife pivoted to the frame, and the spring attached to a support independent of the knife, acting 45 upon the latter only at a point beyond its pivot to press the knife down toward the fingers as it swings over them, substantially as and for the purpose shown.

2. In a lawn-edge trimmer, in combination 50 with a suitable frame having the forwardly-extending fingers provided with cutting-edges, the swinging knife pivoted upon the frame to the rear of the space between the cutting-edges on the fingers, and a spring acting 55 upon the knife only at a point forward of its pivot, so as to press the knife toward the plane of the edges on the fingers, substantially as and for the purpose set forth.

3. In a lawn-edge trimmer, in combination 60 with a suitable frame having fingers with cutting-edges, the swinging knife pivoted to the frame and having the stud forward of its pivot and on the opposite side of the knife from the fingers, and the lever also pivoted 65 to the frame to the rear of the swinging knife and having an arm projecting over the knife provided with a slot engaging the stand on

the knife, substantially as and for the purpose described.

4. In a lawn-edge trimmer, in combination 70 with a suitable frame having the fingers with cutting-edges, the swinging knife pivoted to the frame and having the stud beyond its pivot with inclined sides and situated on the opposite side of the knife from the fingers, 75 and the lever pivoted to the frame to the rear of the knife-pivot and having the slot engaging the stud on the knife, substantially as and for the purpose specified.

5. In combination with the frame having 80 the fingers provided with cutting-edges, the swinging cutter pivoted to the frame and provided with a stud forward of its pivot, the lever also pivoted to the frame and having a slot or notch engaging the stud on the knife, 85 and the spring on the lever also engaging such stud, substantially as and for the purpose shown.

6. In combination with the frame having 90 the forwardly-projecting fingers provided with cutting-edges, the swinging knife pivoted to the frame and provided with the lug with inclined sides situated on the knife forward of its pivot, the knife-actuating lever pivoted to the frame and having a slot or 95 notch engaging the stud on the knife, and the spring attached to the lever and engaging the lug, substantially as and for the purpose set forth.

7. In a lawn-edge trimmer, in combination 100 with a suitable frame having forwardly-extending fingers provided with cutting-edges, the swinging forwardly-extending knife pivoted to the frame and provided with the stud and the arm, respectively forward and to the 105 rear of its pivot, and the actuating-lever pivoted on the frame to the rear of the knife-pivot and having forward of its pivot the notch engaging the stud and the two lugs to engage and act as stops for the arm on the 110 knife, substantially as and for the purpose described.

8. In combination with the frame having 115 projecting fingers provided with cutting-edges, the knife swinging over such edges, pivoted to the frame by a loose pivotal connection, and a spring attached to a part of the machine outside of the knife and pressing the forward portion of the knife down toward the plane of the finger-edges as it 120 swings, substantially as and for the purpose specified.

9. In combination with the frame provided 125 with one or more fingers, each having a cutting-edge, and the pivoted stud on the frame, the swinging knife having the pivotal opening loosely fitting such stud, and a spring attached to a support outside of the knife and acting upon the knife beyond its pivot to hold 130 its portion forward of the pivot down upon the finger or fingers as it swings, substantially as and for the purpose shown.

10. In combination with the frame provided 135 with one or more forwardly-extending fingers,

each provided with a cutting-edge, a pivot, stud on the frame, the knife swinging over the finger or fingers, having the pivotal opening loosely fitting the stud on the frame, and 5 forward of such opening having an upwardly-extending stud on its top, and an actuating-lever provided with a notch or slot engaging such stud, substantially as and for the purpose set forth.

In testimony that I claim the foregoing I do have hereunto set my hand this 22d day of July, A. D. 1889.

HENRY H. DILLE.
